UNITED STATES PATENT OFFICE.

EDWARD BURNS, OF NEW BRITAIN, CONNECTICUT, ASSIGNOR TO THE STANLEY WORKS, OF SAME PLACE.

DOOR-BOLT.

SPECIFICATION forming part of Letters Patent No. 621,896, dated March 28, 1899.

Application filed October 14, 1898. Serial No. 693,497. (No model.)

To all whom it may concern:

Be it known that I, EDWARD BURNS, a citizen of the United States, residing at New Britain, in the county of Hartford and State 5 of Connecticut, have invented certain new and useful Improvements in Door-Bolts, of which the following is a specification.

My invention relates to improvements in door-bolts; and the objects of my improvement are simplicity and economy in construction and efficiency in operation.

In the accompanying drawings, Figure 1 is a front elevation of my door-bolt. Fig. 2 is a transverse section thereof on the line $x-x$ of Fig. 1. Fig. 3 is a central longitudinal section of the same, the handle being lifted up and shown in elevation. Fig. 4 is a front elevation of a portion of the barrel and plate. Fig. 5 is a detached view showing the middle 20 portion of one of the broad sides of the hollow bolt. Fig. 6 is a plan view of the blank from which the hollow bolt is made. Fig. 7 is a plan view of the blank from which the barrel and plate are formed. Fig. 8 is a 25 front elevation of my door-bolt of a modified construction, the bolt being solid instead of hollow and the barrel and plate being formed of separate pieces instead of integral. Fig. 9 is a plan or edge view of the same. Fig. 10 30 is a detached view showing the middle portion of one of the broad sides of the solid bolt, and Fig. 11 is a detached view of the handle.

A A designate the base-plate, and B B the barrel formed integral therewith, said barrel being mainly of an ordinary form, but made square instead of round in cross-section and the longitudinal slot 12 for the shank of the handle C to slide through being widened 35 gradually toward the ordinary transverse locking slots or recesses 13. The blank for forming the barrel and plate is shown in plan view in Fig. 1, and in the main is a well-known form of blank for an integral plate 40 and barrel, and therefore requires no detailed description. I make slits 14 in said blank to form the lugs 15, Fig. 4, which lugs may be turned back at right angles to the plate A A, as indicated by broken lines in Fig. 3, in order 45 to assemble the parts, as hereinafter described.

The bolt D is hollow and is formed from the blank, Fig. 6, in which the broken lines indicate the several bends made in forming said blank into the hollow bolt D. The portion 55 16 of the blank is the same as the broad side 16 of the bolt, 17 the broad side 17 of the bolt, 18 the edge 18 of the bolt, 19 the edge 19 of the bolt, and 20 the ends 20 of the bolt. The slot or hole 21 of the blank is the transverse 60 notch 21 of the bolt for the shank of the handle C to move in, while the lug 22 of the bolt for the cross-head 23 of the handle to rest upon is shown at 22 in the blank as cut on one long side and two ends and is bounded by the 65 broken line on its other long side, on which line it is bent into the position shown in Figs. 2 and 3 inside of the hollow bolt, thereby leaving the broad side 17 with a T-shaped slot or recess, as shown in Fig. 5. The shank of the 70 handle C and its cross-head together form a T-shaped device. When the handle is in a horizontal position and before the bolt is assembled with the plate and barrel, the cross-head 23 of the handle may be passed into the 75 T-shaped recess on the side 17 of the bolt, and when so inserted it may be turned up into the position shown in Fig. 3. As before suggested, the lugs 15 at one end of the plate A A are turned down, as indicated by broken 80 lines in Fig. 3, to elongate the opening at the back of the barrel. One end of the bolt is then passed through that part of the barrel that is farthest from the said lugs 15 until the other end of said bolt passes the said lugs 15 85 and is opposite the opening in the back of the plate A A. The bolt is then swung edgewise into the barrel, letting the handle pass through the slot 12. After the bolt is thus placed in the barrel the lugs 15 are bent back into the 90 same plane as the rest of the plate A A, and coming in the rear of the edge 19 of the bolt hold the bolt from disengagement with the barrel. The bolt, as in the ordinary round bolts, is locked in either extreme position by the handle and transverse notches and permitted to move longitudinally when the shank of the handle is in the longitudinal slot 12 of the barrel; but instead of having the bolt partially 95 rotate and constitute the axis of the handle 100 the bolt being square is held against rotation and the handle is hung on an axis of its own

within the non-rotating bolt. The slotted hollow bolt and the cross-head of the handle, together with the lug 22, hold the handle securely within the bolt and at the same time 5 permit it to swing freely on its axis for locking and unlocking the bolt. The beveled ends or widened portions of the slot 12 prevent the shank of the handle from being caught on the corners in case the handle is 10 not at first turned up sufficiently to center itself in the slot 12. Besides being a cheap construction the handle will always turn easily, as it does away with the friction of the bolt within the barrel that is present when 15 the bolt rotates therein. Besides this greater security is had, as it is impossible for any one to unlock the bolt by rotating the barrel.

In Figs. 8 to 11 I show a modification of my bolt as to some features; but the general construction and the advantages relating to the operation are the same as hereinbefore set forth for the construction first described. In the modification the plate A' and the barrel B' are made from separate pieces and put together by riveting the ends of the lugs on the barrel within holes in the plate, as in ordinary door-bolts; but the barrel, like that first described, is square or rectangular in cross-section. So, also, is that of the solid bolt. I form 20 the T-shaped slot 24, Fig. 10, and the handle C' with a cross-head 23, as in the construction first described. Before the barrel and plate are assembled I slip the cross-head of the handle into the T-shaped slot in the bolt, then 25 pass the bolt into position in the barrel, and secure the barrel to the plate, after which the handle can swing freely, as before described, but cannot be detached without separating the barrel from the plate.

While I have shown the solid bolt D', Figs. 30 8 and 9, as placed in the barrel that has its plate formed in a separate piece from said barrel, it is evident that the hollow bolt (shown in Figs. 1, 2, and 3) could, if desired, be placed in said barrel, and a solid bolt may be used 35 in a barrel and plate as formed from the one-piece blank, Fig. 7.

It is apparent that some changes from the specific construction herein disclosed may be made, and therefore I do not wish to be understood as limiting myself to the precise form of construction shown and described, but desire the liberty to make such changes in working my invention as may fairly come within the spirit and scope of the same. 50 55

I claim as my invention—

1. A door-bolt, consisting of the combination of a plate, a barrel of a rectangular form in cross-section mounted on said plate and having a longitudinal slot and locking-notches, a bolt of a rectangular form in cross-section arranged to slide longitudinally within the said rectangular barrel, and a swinging handle, pivoted within a recess in that side of said bolt which is farthest from the said plate, substantially as described. 60 65

2. The combination in a door-bolt of the plate and barrel, a non-rotary bolt arranged to slide longitudinally in said barrel and having a transverse notch opening into a side recess and therewith forming a T-shaped recess, and a handle having a cross-head resting within said T-shaped recess and held in place therein by securing the barrel within the bolt substantially as described. 70 75

3. In a door-bolt, the hollow bolt, having the T-shaped recess and the lug 22 for forming the bottom of said recess and confining therein the swinging handle, substantially as described. 80

4. The combination of the integral plate and barrel open at the back, and having lugs adapted to be bent back adjacent to one end of the opening in the back of the barrel to elongate said opening, a bolt confined by 85 the said barrel and plate with one end of the bolt in the completed article held in place by means of the said lugs, substantially as described.

EDWARD BURNS.
